UNITED STATES PATENT OFFICE.

EARLE C. BACON, OF NEW YORK, N. Y.

DESIGN FOR A PITMAN FOR ROCK-CRUSHERS.

SPECIFICATION forming part of Design No. 32,658, dated May 15, 1900.

Application filed March 7, 1900. Serial No. 7,744. Term of patent 14 years.

To all whom it may concern:

Be it known that I, EARLE C. BACON, a citizen of the United States, residing in the city of New York, borough of Brooklyn, in the 5 county of Kings and State of New York, have invented and produced a certain new and original Design for a Pitman for Rock-Crushers, of which the following is a full, clear, and exact specification, reference being had to 10 the accompanying drawing, forming a part thereof and showing a perspective view of the pitman.

The leading features of my design are the hollow cylindrical head, the converging webs 15 extending tangentially downward therefrom and joined and thickened along the line of junction, and the connecting transverse webs forming a chamber below the head.

The cylindrical head is marked A and has 20 a swell A' on each side at about the center, in which are the channels a a, leading to the interior. The webs A² A² flow tangentially from the head and extend downward there-

from and are joined on the line of convergence in a thickened portion A³, having a 25 rounded under face and the laterally-projecting lips A⁴ A⁴.

The webs A² A² are connected by the transverse webs A⁵ A⁵ and with the latter form the chamber a'. Each web A² has the projecting lugs A⁶ A⁶ thereon and is provided with an opening a², leading to the chamber a'. 30

On the upper face of the head are the bosses A⁷ A⁷ and a loop or eye A⁸, and the swells thereon are each made with the knuckles A⁹ A⁹ and lugs A¹⁰ A¹⁰, as shown. 35

I claim—

The design for a pitman for rock-crushers herein shown and described.

In testimony that I claim the design above 40 set forth I affix my signature in the presence of two witnesses.

EARLE C. BACON.
